DESIGN FOR A FOUNDATION GARMENT OR SIMILAR ARTICLE

Florence Murray, Wichita, Kans.

Application June 29, 1938, Serial No. 78,135

Term of patent 7 years

To all whom it may concern:

Be it known that I, Florence Murray, a citizen of the United States of America, residing at Wichita, in the county of Sedgwick and State of Kansas, have invented a new, original, and ornamental Design for a Foundation Garment or Similar Article of which the following is a specification, reference being had to the accompanying drawing, forming part thereof.

Figure 1 is a front view of the foundation garment showing my design.

Figure 2 is a rear view thereof.

The foundation garment comprises feet, leg

and trunk portions having the contour and shape of the human body, a front central panel extending from the waist to the crotch, an upwardly extending front-chest member, straps extending from the top of the chest member upwardly, rearwardly and downwardly to the waist line at the rear of the trunk portion, and a central back member extending between the two straps, as shown.

I claim:

The ornamental design for a foundation garment or similar article, as shown and described.

FLORENCE MURRAY.
